Des. 215,130
Patented Sept. 2, 1969

215,130

HEEL MEMBER FOR A SHOETREE

Abraham Messinger, 50 Park Ave.,
New York, N.Y. 10016

Filed Apr. 16, 1968, Ser. No. 11,474

Term of patent 14 years

Int. Cl. D28—99

U.S. Cl. D86—10

FIGURE 1 is a perspective view of a heel member for a shoetree embodying my design,

FIGURE 2 is a top plan view of the heel member,

FIGURE 3 is a side elevational view of the heel member,

FIGURE 4 is a bottom plan view of the heel member,

FIGURE 5 is an end elevational view of the heel member as seen from the right in FIGURE 3, and

FIGURE 6 is an end elevational view of the heel member as seen from the left in FIGURE 2.

I claim:

The ornamental design for a heel member for a shoetree, as shown.
